DESIGN FOR AN IRONING MACHINE CABINET

Herman A. Sperlich and Johannes H. Uhlig,
Detroit, Mich.

Application January 30, 1935, Serial No. 55,157

Term of patent 7 years

To all whom it may concern:

Be it known that we, Herman A. Sperlich and Johannes H. Uhlig, both citizens of the United States and residents of the city of Detroit, Wayne County, Michigan, have invented a new, original, and ornamental Design for Ironing Machine Cabinet, of which the following is a specification, reference being had to the accompanying drawing, forming part thereof.

Figure 1 is a front elevational view of a cabinet, suitable for the housing of the mechanism

of an ironing machine or the like, showing our new design.

Figure 2 is an end view of the same.

The figures are lined to indicate black ornamentation.

We claim:

The ornamental design for an ironing machine cabinet, substantially as shown and described.

HERMAN A. SPERLICH.
JOHANNES H. UHLIG.
